A. MESSINA,
ACETYLENE GAS LAMP,
APPLICATION FILED APR. 16, 1915.

1,187,538.

Patented June 20, 1916.

INVENTOR
ANTHONY MESSINA
BY *Frank & Cook, Jr., Jr.*

UNITED STATES PATENT OFFICE.

ANTHONY MESSINA, OF BENLD, ILLINOIS.

ACETYLENE-GAS LAMP.

1,187,538.

Specification of Letters Patent. Patented June 20, 1916.

Application filed April 16, 1915. Serial No. 21,902.

To all whom it may concern:

Be it known that I, ANTHONY MESSINA, a subject of the King of Italy, a resident of Benld, in the county of Macoupin, State of Illinois, have invented certain new and useful Improvements in Acetylene-Gas Lamps, of which the following is a full, clear, and exact description, reference being had to the accompanying drawing, forming a part of 10 this specification.

My invention relates to acetylene gas lamps and has for its object to provide a filter in communication with the gas conducting pipe which does not readily become 15 damp and clogged, and to provide a reflector removably attached to the gas conducting pipe, the said reflector having a removable frangible burner secured thereto so that the reflector and burner may be handled together in removing and attaching them, 20 thereby avoiding breakage of the burner.

Figure I is a side elevation, partly in section, of a miner's lamp embodying the features of my invention. Fig. II is a vertical 25 section of the lamp. Fig. III is a horizontal section taken approximately on the line III—III, Fig. II.

A designates a water receptacle having a bottom wall 1 and provided with a screw 30 threaded neck 2.

B designates a carbid receptacle having a neck 3 at its upper end which is screwed into the neck of the water receptacle. A water tube 5 passing through the water receptacle 35 A and bottom wall 1 extends into the carbid receptacle. This water tube is provided with an inlet port 6 adjacent to the bottom wall 1 so as to permit the escape of water from the lower portion of the water recep- 40 tacle.

7 designates a valve member in the form of a rod having a tapered valve seat 8, near its lower end, adapted to engage the tapered lower portion of the water tube 5 to prevent 45 the escape of water into the carbid receptacle except as needed. The upper portion of the valve member 7 is screwed into the upper portion of the water tube. The screw threaded valve member 7 is provided with 50 an operating handle 9 at its upper end. The valve member may be moved toward and away from the lower end of the water tube by rotating the handle 9.

10 designates a cap screwed onto the upper end of the water tube 5, and 11 designates 55 packing arranged between said cap and tube.

The lower end of the valve member 7 is provided with a reduced extension 7^a which passes through the reduced lower end of the water tube so as to serve as means for clean- 60 ing the tube at this point.

12 designates a gas conducting tube extending from an opening in the bottom wall of the water receptacle to an opening in a side wall thereof, said conducting tube being 65 provided with a pocket member 13 at its outer end.

14 designates a reflector having a neck screwed onto the pocket member 13 and provided with a sleeve for a removable frangible 70 clay tip or burner 15. A gasket 16 is arranged between the pocket member 13 and the reflector 14.

17 designates cotton or other suitable filtering material, arranged in the pocket member 13 so as to filter the gas immediately before it reaches the burner 15. By filtering the gas immediately before it reaches the burner I prevent the carbide dust and other matter, which accumulates in the pipe 12, 75 from passing into the small discharge port in the burner. Another advantage of this structure is that the filtering material may be readily removed and replaced by simply unscrewing the reflector from the pocket 80 member 13.

20 designates a tube for conducting gas from the carbide receptacle to the upper portion of the water receptacle. This tube passes entirely through the water receptacle 90 and its lower end is located in the carbide receptacle.

21 designates a discharge port, formed in the upper portion of tube 20 to permit the discharge of gas near the top wall of the 95 water receptacle. The tube 20 is fixed to the screw threaded member 22, the latter being fixed to the top wall of the water receptacle.

23 designates a cap screwed onto the upper end of the threaded member 22 to prevent 100 the escape of gas. A scraper 24, passing through the tube 20, is fixed to the cap 23. This scraper 24 is preferably a flexible spiral member adapted to be rotated in the tube 20. The cap 23 may be readily unscrewed and removed with the result of rotating and slid-

ing the scraper in the tube 20, thereby removing carbid and other matter from said tube.

The water receptacle is preferably made 5 air tight or water tight so as to prevent the escape of water to the exterior of the lamp. When the device is in service the gas flows through the tube 20 and into the upper portion 10 of the water receptacle to compensate for the displacement of the water and the pressure of this gas is utilized to force the water into the carbid receptacle.

25 designates ribs pressed from the carbid receptacle to serve as hand grips in securing 15 the carbid receptacle in the threaded neck of the water receptacle.

26 designates a tube extending from the top wall of the water receptacle, and 27 is a

cap forming a closure for said tube. This cap normally closes the tube 26 but it may be 20 readily removed to permit the introduction of water into the water receptacle.

A clay tip or burner 15 such as I have shown is readily broken if it becomes tightly wedged in its seat and an attempt is made to 25 remove it for the purpose of cleaning the burner and the passageway back of the burner,—a new tip or burner being as readily substituted for the tip or burner removed.

I claim:

An acetylene gas lamp comprising a removable reflector having a tip or burner sleeve and a removable frangible clay tip or burner secured in the said tip or burner sleeve.

ANTHONY MESSINA.
